COMPRESSOR CONTROL SYSTEM

Charles A. Corson, Painted Post, N.Y., and Wade W. Paschke, Mountain Lakes, N.J., assignors to Ingersoll-Rand Company, New York, N.Y., a corporation of New Jersey

Filed Mar. 6, 1956, Ser. No. 569,782

12 Claims. (Cl. 230—25)

This invention relates to control systems and more particularly to load controllers for motor driven gas compressors.

The control of this invention is designed particularly for use in compressor installations wherein the motor load varies throughout a loading cycle because of variations in inlet or discharge pressure of the compressor, and more particularly to such installations wherein the overall variations in such pressure is in one direction only—i.e., an overall pressure increase or pressure decrease. An example of such an installation is where a compressor is connected to fill a container with a gas, compressing the gas from a pressure of, for example, 100 pounds per square inch (p.s.i.) to 900 p.s.i. Without a load control, or regulator, the compressor driving motor would have to be, in such an installation, of sufficient horse power to compress the gas from 100 p.s.i. to 900 p.s.i. at the full capacity of the compressor. However, the maximum horse power demand on the motor would occur during only a relatively short period of time at the end of the cycle.

With the present invention, the compressor capacity is controlled in response to the load on the motor in such a manner that the compressor is unloaded in a step by step fashion so that as the discharge pressure of the compressor increases, the capacity of the compressor is proportionately reduced. Moreover, this control is designed to unload the compressor in such a fashion that the driving motor is operated at approximately its rated horse power during the entire cycle. Inasmuch as the control is operated in accordance with the load on the driving motor, the controller will operate effectively regardless of the value of the inlet pressure within broad limits—so long as this value remains relatively constant throughout a load cycle once the cycle has started.

It is one object of this invention to provide a control for motor driven compressors adapted to operate in installations wherein the inlet or discharge pressure of the compressor varies over a wide range during a cycle, whereby the compressor capacity is controlled to load the driving motor to substantially its full rated capacity over the entire cycle.

A further object is to provide such a control with a safety control operating substantially independently of the control actuated in response to variations in motor load.

Further objects will become apparent from the following specification and drawing in which,

Fig. 1 is a diagrammatic view of the unloader,

Fig. 2 is a schematic view of the details of a portion of the unloader,

Fig. 3 is a schematic view of a compressor to be controlled,

Fig. 4 is a graph showing the brake horse power of the motor compared to the discharge pressure of the compressor, and

Fig. 5 is a graph showing the quantity of air pumped by the compressor for a given discharge pressure.

2

OPERATION AND CONSTRUCTION IN GENERAL

Loading the compressor

Referring to the drawings, and first to Fig. 3, the compressor controlled by the unloader is illustrated as a two stage compressor driven by an electric motor 8 and having three low pressure stage compressors 10, 12 and 14 and three high pressure stage compressors 16, 18 and 20. All of the compressors are provided with 10 solenoid operated free air unloader valves, designated by FAU1, FAU3, FAU5 and FAU8, there being one such valve at each end of each compressor, and there is provided additionally clearance pocket valves, designated by CP2 and CP4, for two of the low pressure compressors 12 and 14. Thus positioned each such clearance or unloader valve controls part only of the compressor capacity. Each valve is connected with a means, or valve operating mechanism, for being separately operated, which means can be of any conventional form such as the air operated diaphragm 22 connected for the supply of actuating fluid through a three way solenoid operated valve 26 (identified in general by UNL2 in Fig. 2).

In installations wherein the starting discharge pressure of a loading cycle is relatively low and the final pressure is relatively high, it is normally desirable to load the compressor to one-half or two-thirds of its capacity in one step and thereafter complete the loading of the compressor in a plurality of small loading steps. 25 The degree to which the compressor is loaded in the first step is determined by the particular installation. It is generally known what the normal range of initial and maximum discharge pressures will be for any given installation, and accordingly, the control is designed to 30 initially load the compressor to a capacity, for a given discharge pressure, which will closely approximate a load on the driving motor at or near the rated capacity of such motor.

With the control disclosed it is assumed by way of 40 example that it is desirable to initially load the compressor to approximately two-thirds of its capacity. Accordingly, the UNL8 valve operating mechanism operates to close all FAU8 valves thereby substantially fully loading the high pressure stage of the compressor and 45 loading the low pressure stage to one-half capacity. Thereafter the low pressure stage is loaded to full capacity in a step by step fashion by the means for operating other valves—e.g., UNL1, UNL3, closing, in sequence, the valves FAU1, FAU3, FAU5 and CP2 and 50 CP4, although not necessarily in the order named.

The step by step loading is accomplished by means of a sequence timer (designated ST in Fig. 1), connected to operate a plurality of switches (ST1-ST5) each of 55 which in turn is connected to energize the solenoid of a three way valve, such as valve 26 (Fig. 2). More particularly, when the compressor is started up, the sequence timer ST is energized to close in numerical order the switches ST1, ST2, ST3, etc. The timer ST may be of any commercial form adapted to close the switches in delayed sequence. For example it may be desired to close one switch every ten seconds after the compressor is started such that the low pressure stages are completely loaded in 50 seconds.

Load responsive unloading of compressor

Additionally connected to and cooperating with the loading control is the unloading control designed to prevent the load on the motor from exceeding the rated horse power. This unloading control includes a control element, such as a contact making watt meter (CFW) and associated switch elements, responsive to

variations in load on the driving motor and connected to the means for operating the unloading valves.

The control element is energized and de-energized alternately as the motor load exceeds and falls below a predetermined value. Each time the control element is energized it operates said means to partially unload the compressor and reduce the motor load. More particularly, whenever the load on the driving motor exceeds, for example, 1,050 horse power, the watt meter is closed, or energized, thereby operating, through appropriate connecting elements, the means for opening one of the unloading valves. The operation of the unloading valve lowers the capacity of the compressor approximately one-twelfth which lowers the horse power demand on the motor to say, for example, 950 horse power. This lowering of the power demand below the 1,050 value de-energizes the watt meter. Thereafter the load on the compressor will increase proportionately with the increase in discharge pressure of the compressor until such time as the load on the motor again exceeds 1,050 thereby energizing the watt meter to again further unload, or reduce the capacity of, the compressor.

Time delay unloading of compressor

In the event the discharge pressure condition or loading condition at anytime in the cycle is such that when the watt meter is energized to partially unload the compressor and the unloading step is not sufficient to reduce the motor load to a value whereat the watt meter is de-energized, a safety time delay control comes into operation to reduce the capacity of the compressor. This safety control is energized to operate the next unloading step of the cycle in the event the watt meter is not de-energized within a predetermined lapse time (e.g., 3 seconds) after being energized. If this additional unloading step is not sufficiently great to drop the motor load below value at which the watt meter is de-energized, then 4 seconds later the safety mechanism will trigger the succeeding unloading step and so on until the motor load is dropped to a value whereat the watt meter is de-energized.

It is to be noted that the safety time delay is set such that under normal operating conditions the watt meter is de-energized before the safety device is operated to further unload the compressor. Inasmuch as watt meter and safety device are de-energized at the same time, it is immaterial to the operation of the control how long it takes before the load on the compressor builds up to a value whereas the watt meter is again energized.

CONSTRUCTION IN DETAIL

Loader

Referring now in more detail to the particular construction of the control shown by way of illustration, Fig. 1 is a diagrammatic view of the various elements involved and show their interconnections. These elements are of the electrically operated type and are shown connected between power lines 28 and 30. The solenoid unloading valve UNL8 comprises a three way valve element similar to valve 26 (Fig. 2) connected to a plurality of motors similar to motor 22, one motor being provided for each FAU8 valve. When the compressor is started, UNL8 is energized to operate all FAU8 valves to load the compressor to approximately $\frac{2}{3}$ of its capacity.

Energized simultaneously with UNL8 is UNL7 to close FAU7. Connected in series with UNL7 is a normally closed pressure switch PS connected to the discharge of the compressor and designed to open whenever the discharge pressure exceeds some predetermined value, as for example, 800 p.s.i. Opening of PS de-energizes UNL7 to open FAU7. The circuit containing UNL7 is provided merely to insure that too great a pressure differential can not exist across the high pressure stage. This is a desirable safety feature, but it is

not a feature necessary to the operation of the unloader.

Connected to the remaining valves are time delay elements ST and ST1-ST5 for completing the loading cycle specifically. Sequence timer ST is also energized simultaneously with UNL7 and UNL8 and is connected to operate in time delayed sequence the switches ST1-ST5. These switches ST1-ST5 and solenoid unloader valves UNL1-UNL5 are connected, respectively, in circuits 32, 34, 36, 38 and 40 so that as each switch is closed, the numerically corresponding unloader valve is energized. It will be assumed for purposes of illustration that the sequence timer is designed to close the switches ST1-ST5 in numerical order at 10 second intervals after the compressor is started and that UNL1 is connected to operate FAU1, UNL2 is connected to operate CP2, UNL3 is connected to operate FAU3, UNL4 is connected to operate CP4, and UNL5 is connected to operate FAU5.

With the loading circuit described, upon supplying power to lines 28 and 30, UNL7 and UNL8 are immediately energized to load the compressor to approximately two-thirds of its capacity. Ten seconds later the sequence timer closes ST1 thereby completing circuit 32 to operate UNL1 closing free air unloader valve FAU1 to further increase the capacity of the compressor; ten seconds after the operation of ST1, the sequence timer closes ST2 to complete circuit 34 and operate UNL2 closing clearance pocket CP2 to further increase the compressor capacity. Then ST3, ST4 and ST5 are closed sequentially at ten second intervals to close FAU3, CP4 and FAU5, respectively, to completely load the compressor.

Unloader

Interconnected with the loading circuit is the unloading circuit which cooperates with but operates substantially independently of the loading circuit to maintain the load on the driving motor at or slightly below its rated capacity by controlling the capacity of the compressor. More particularly, this circuit includes the contact making watt meter CFW in circuit 42 in which circuit a master relay RA is connected to be energized and de-energized by the closing and opening of CFW. The relay RA is, in turn, connected to operate the master elements or switches RA1 and RA2 connected in control circuit 44 and set up circuit 46, respectively. Each master switch RA1 and RA2 is connected through branch circuits to control a plurality of control elements or relays R1-R11, with RA1 connected to control the odd numbered control relays (e.g., R1, R3) and relay RA2 being connected to control even numbered auxiliary relays (e.g., R2, R4). The control relays are connected to operate a plurality of switches identified by R1a, R1b, R2a, R2b, and so on, with all switches with an R1 prefix being controlled by the R1 control relay, all prefix R2 switches being controlled by the R2 relay and so on.

It is to be noted that all R prefix switches are shown as being either normally open or normally closed (the switches shown closed across the schematic points are normally closed). Whenever the relay controlling the particular switch is energized, the switch action is reversed. For example, RA1 is a normally open switch and accordingly when the relay RA is energized, RA1 is closed, whereas switch RA2 which is normally closed is simultaneously opened. When the relay RA is de-energized, the normally open switch RA1 will open and the normally closed switch RA2 will close.

The RA1 circuit 44 comprises a plurality of branch circuits 44a, 44b, 44c, 44d, 44e and 44f, connected in parallel relative to each other but in series with the switch RA1. Connected in branch circuit 44a is a normally closed switch R2c and in branch 44f is a normally open switch R10b. Connected in each of the other branch circuits 44b, 44c, 44d and 44e is a normally open switch and a normally closed switch identified, respectively, as R2b and R4c, R4b and R6c, R6b and R8c, and R8b and

R10c. Connected respectively, in branches, 44a, 44b, 44c, 44d, 44e and 44f are control relays R1, R3, R5, R7, R9 and R11 each of which is in turn connected to operate a switch in the loading circuit having the same letter and numeral prefix. These switches are designated R1c, R3d, R5d, R5e, R7d, R9d and R11b, and are connected, respectively, in the loading circuits 32, 34, 36, 34a, 34a, 38 and 40.

With this arrangement when R1 of the unloading system is energized, switch R1c will be opened to break circuit 32 and thereby operate UNL1. Similarly, when R3 of the unloader circuit is energized, switch R3d is opened to operate UNL2 and so on. In other words, whenever one of the branch circuits of circuit 44 is completed, the compressor is partially unloaded.

The unloading circuit 46 is similar to circuit 44 and comprises a plurality of branch circuits 46a, 46b, 46c, 46d and 46e connected in parallel relative to each other but in series with the switch RA2. Connected in each branch circuit 46a-46e, respectively, is a normally open switch and a normally closed switch identified, respectively, as R1b and R3c; R3b and R5c; R5b and R7c; R7b and R9c; and R9b and R11c. Also connected respectively, in branches 46a-46e are control relays R2, R4, R6, R8 and R10 each of which in turn is connected to operate the switches in the control circuit having the same letter and numeral prefix.

Connected between each of the branch circuits of circuit 44 and 46 and between circuits 44a and 48 is a normally open switch. Specifically, switch R1a connects circuits 48 and 44a, switch R2a connects branch circuit 44a and 46a, R3a connects 46a to 44b, R4a connects 44b to 46b, R5a connects 46b to 44c, R6a connects 44c to 46c, R7a connects 46c to 44d, R8a connects 44d to 46d, R9a connects 46d to 44e, R10a connects 44e to 46e, and R11a is connected between 46e and 44f.

With the circuits 44, 46 and 32-40 just described everytime the CFW is closed, after the first step, a branch circuit of 44 is closed to

(a) Open a switch (R3c) in the preceding branch circuit (46a) of circuit 46 to prevent premature operation of the succeeding 46 branch circuit (46b),

(b) Closes a switch (R3b) in the succeeding branch circuit of circuit 46 (46b) to set up this circuit to be completed on subsequent closing of RA2,

(c) Closes a preceding cross switch (R3a) to "lock in" the energized circuit, by locked in energized it is meant that subsequent opening of the switch RA1 will not de-energize that branch circuit, and

(d) Breaks one of loading circuits (opens R3d) to partially unload the compressor. (All numerals within parentheses in (a)-(d) are by way of illustration.)

Whenever the CFW is opened, a branch circuit of circuit 46 is completed to carry out steps (a) and (b) and (c) just described, except relative to preceding and succeeding branch circuits of circuit 44.

OPERATION CIRCUITS 44 AND 46

The operation of each step of the branch circuits of 44 and 46 is substantially identical other than the first step of circuit 44. Accordingly, the operation of only circuits 44a, 44b and 46a of the load responsive unloading circuit will be described.

Assuming that the loading circuit has loaded the compressor to full capacity and that the horse power load on the compressor exceeds 1,050 brake horse power, the CFW will close completing circuit 42 and energizing the auxiliary relay RA which will close switch RA1 and open switch RA2.

The closing of switch RA1 completes circuit 44a to energize the control relay R1 which simultaneously:

(1) Opens switch R1c in circuit 32 thereby de-energizing UNL1 such that FAU1 is opened to partially unload the compressor and

(2) Closed switch R1b in branch circuit 46a setting 75

up this circuit to be triggered by the subsequent closing of switch RA2.

(3) Closes switch R1a locking R1 in circuit 48 such that subsequent operation of the switch RA1 will in no way effect R1.

The partially unloading of the compressor will result in the lowering of the horse power demand on the motor such that it falls below 1,050 brake horse power and the watt meter CFW will open thereby de-energizing RA to open RA1 and close RA2. Closing of RA2 completes branch circuit 46a energizing R2 which simultaneously:

(1) Open switch R2c to prevent premature triggering of unenergized branches of circuit 44, and

(2) Closes R2b setting up circuit 44b to be triggered by the subsequent closing of RA1, and

(3) Locks in with circuit 48 by closing switch R2a.

Thereafter if the horse power demand on the motor again rises above 1,050 brake horse power, the contact making watt meter at CFW will close energizing RA to close RA1 and open RA2, completing branch circuit 44b, energizing R3 to (1) close R3a locking in R3 through line 48, (2) close R3b to set up circuit 46b, (3) operate R3d to de-energize UNL2 and open clearance pocket CP2 and further unload the compressor, and (4) open R3c to prevent premature triggering of unenergized branch circuits of circuit 46.

Alternate opening and closing of the CFW in response to the load demand on the motor will thereafter energize circuit 46b to set up 44c, then trigger circuit 44c to operate UNL3 (and energize UNL2 by closing R5e to close CP2 if branch circuit 34a, described hereinafter, is used), then to complete circuit 46c to set up circuit 44d to be subsequently triggered to again operate UNL2 and open CP2 where circuit 34a is used, then complete circuit 46d to set up circuit 44e to be triggered to operate UNL4, then complete circuit 46e to set up circuit 44f to be triggered to operate UNL5 and thereby complete the unloading cycle.

It is to be noted that a parallel circuit 34a is provided in line 34 connected on the opposite sides of switch R3d. This parallel circuit includes a normally open switch R5e and normally closed switch R7d. The purpose of this parallel circuit is to give a finer degree of load control without increasing the number of clearance pockets or loading valves. More particularly it operates to close clearance pocket CP2 at the same time FAU3 is opened, and to open it subsequently when R7d operates. This circuit may or may not be used as desired without otherwise effecting the operation of the control system.

TIME RESPONSIVE UNLOADER

Structure

Cooperating with the loading and unloading systems or circuits is the time delay mechanism energized and de-energized simultaneously with the CFW and interconnected with the circuits 44 and 46. This mechanism acts within a predetermined time after the CFW is closed to complete one of the branch circuits 46 and within a second predetermined lapse time to operate one of the branch circuits 44 to complete one of the unloading stages of the cycle. Moreover this unloading process will continue in delayed step by step fashion until such time as the CFW is operated to de-energize the time delay mechanism. Practically what this means is that if after the CFW is closed to trigger one of the unloading steps of the cycle and this unloading step is not sufficient to drop the load on the motor to something below 1,050 brake horse power to open the CFW, then the time delay mechanism comes into operation to further unload the compressor in a step by step fashion until such time as the horse power load on the motor drops below 1,050 thereby opening the CFW.

The time delay mechanism comprises the following time delay circuit. A pair of time delay switches TR1 to and

TR2_{to}, connected in a series in circuit 42 on the opposite sides of the CFW, and switch TR1_{tc} connected in circuit 48. The TR1 switches are controlled by a timing relay TR1 connected in circuit 42 and in parallel with switch TR1_{to}. The TR2_{to} switch is controlled by a timing relay TR2 connected in series in circuit 48.

It is to be noted that the switches designated of the suffix _{to} are of the type which when the associated timing relay is energized will open within a predetermined time thereafter if the timing relay remains energized, and will close immediately when the timing relay is de-energized. The switch TR1_{tc} is of the type that closes within a predetermined time after the timing relay TR1 is energized, but opens immediately when the timing relay is de-energized. The time delay of these switches are set such that, for any given installation, the unloading circuit controlled by the watt meter CFW will normally control the unloading of the compressor—i.e., the delay in operation of these switches is sufficiently long to permit the unloading circuit to operate and complete one unloading step of the cycle before the time delay mechanism comes into operation. Thus the time delay mechanism serves only as a safety device where any one unloading step is not sufficient to lower the horse power demand on the motor to something less than the value at which the watt meter is opened.

Operation

The operation, in detail, of the time delay mechanism is as follows. Whenever the watt meter CFW closes completing circuit 42, the timing relay TR1 is energized so that TR1_{to} and TR1_{tc} open and close, respectively, in for example three seconds. Assume during this three second period that the unloading circuit controlled by the CFW has triggered circuit 44a and partially unloaded the compressor by operating UNL1, and that this unloading step is not sufficient to lower the horse power load on the motor to a value low enough to open CFW. Then, on the expiration of three seconds, TR1_{tc} closes completing circuit 48 thereby energizing the timing relay TR2 which, in turn, energizes TR2_{to} such that it will open in approximately one second.

Simultaneously, with the closing of TR1_{tc}, the switch TR1_{to} opens thereby breaking circuit 42 and de-energizing the auxiliary relay RA. The effect of de-energizing RA is the same as if CFW opened. This means that the switches RA1 and RA2 are reversed thereby completing circuit 46a, locking in control relay R2 and setting up branch circuit 44b to be triggered by RA when it is again energized.

After a lapse of one second from this operation, TR2_{to} opens thereby de-energizing TR1 and immediately closing switch TR1_{to} and opening TR1_{tc} to de-energize TR2 and thereby close TR2_{to} completing circuit 42. This action is the same as if CFW closed, hence RA is energized to close RA1 completing circuit 44b to operate UNL2. This completes one step of the timing cycle and one complete step of unloading of the compressor.

This timing unloading step is continuously repeated, taking a total of four seconds for each step, with one of the solenoid unloading valves UNL being operated by every completed step of operation of the time delay mechanism. The time delay mechanism will continue to operate to unload the compressor in a step by step fashion and in the same manner as if the CFW were opening and closing until such time as the load on the compressor falls below a value at which the CFW is opened thereby de-energizing TR1 and halting the operation of the time delay mechanism.

The foregoing operational steps are shown diagrammatically hereinafter, but it is to be understood that the diagram portion relating to the time delay circuit occurs only if the CFW is not opened within three seconds after it is closed.

DESCRIPTION OF FIGURE 2

Referring now to Figure 2, the auxiliary relay RA and

control relays R1-R5 are shown in detail. Only the details of this portion of the circuit is shown, for, as previously mentioned, the remaining portion of the circuit will become obvious and is substantially a repetition of what is shown. It is apparent that by merely adding additional branch circuits to 46 and 44, the number of unloading steps may be multiplied indefinitely without changing the general pattern of control.

It is assumed that R1 and R2 have been previously energized and locked in position so that switches R1_a, R1_b, R2_a, and R2_b will remain closed and R1_c and R2_c will remain open for the remainder of the loading cycle. Moreover it is assumed that the CFW has just closed thereby energizing RA to close RA1 and open RA2. The closing of RA1 energizes R3 (circuit 44b is completed through switch R2_b, R4_c, and thence through the control relay R3). As shown R3 has just been energized thereby closing switches R3_a and R3_b and opening switches R3_c and R3_d.

Opening of switch R3_d de-energizes the three-way solenoid of UNL2 to exhaust air from the valve unloader 22 and hence operates clearance pocket CP2 to partially unload the compressor. The opening of R3_c prevents the completion of the branch circuit 46b through R1_b, R2_a and thence back through R1_a to line 48.

The closing of R3_a completes a circuit through R2_a and R1_a to lock in relay R3. The closing of R3_b sets up branch circuit 46b such that on subsequent opening of CFW to close RA2 it will complete circuit 46b.

When RA2 closes, it completes a circuit 46b through R3_b, R5_c and actuates R4 into its alternate position closing switches R4_a and R4_b and opening R4_c. Closing of R4_a locks in control relay R4 through R3_a, R2_a and R1_a. Closing of R4_b sets up circuit 44c to be triggered by subsequent closing of the CFW, and opening of R4_c prevents premature triggering of circuit 44c through R2_b, branch circuit 44b, R3_a, R2_a, R1_a, and line 48.

DESCRIPTION OF COMPLETE LOAD CYCLE

Reviewing briefly a full operating cycle of the motor compressor unit, the steps are as follows:

Step A.—Assuming the compressor is started unloaded, the control circuit is energized thereby energizing UNL8 and closing the eight FAU8 valves to load the compressor to approximately two-thirds of its capacity.

Simultaneously, with this action UNL7 is energized, assuming the discharge pressure of the compressor is below a value at which switch PS will be opened, and accordingly FAU7 is closed.

Step B.—Energized simultaneously with the energizing of the control circuit is the sequence timer ST which operates the switches ST1-ST5 in numerical order at, for example 10 second intervals thereby operating in sequence and at the same interval UNL1-UNL5 to close FAU1, CP2, FAU3, CP4 and FAU5 and fully load the compressor in a step by step fashion.

Step C.—Assuming the discharge pressure of the compressor reaches a value whereat the motor load exceeds some predetermined value corresponding approximately to the rated horse power of the compressor (e.g. 1,050 horse power), the contact making watt meter CFW will close energizing RA to complete and lock in circuit 44a and thereby operate R1 to open circuit 32 and de-energize UNL1 and open FAU1 to partially unload the compressor.

Step C reverse.—Assuming the operation of FAU1 lowers the demand on the motor to a value below 1,050 horse power, the CFW will open triggering and locking in branch circuit 46a to set up branch circuit 44b.

Step D.—When the motor load again exceeds 1,050 horse power, CFW closes energizing RA to complete and lock in circuit 34, de-energizing UNL2 and opening CP2.

Step D reverse.—When the load demand falls below 1,050 horse power, the CFW opens, circuit 46b is completed to set up circuit 44c.

changes and modifications may be made without departing from the spirit of the invention as set forth in the appended claims.

We claim:

1. The combination with a motor driven compressor having a plurality of unloading valves, each valve controlling part only of the compressor capacity, of a load controller comprising means operatively connected for operating said unloading valves, a wattmeter automatically responsive to variations in load on the driving motor connected to be energized and de-energized alternately and respectively as the motor load exceeds and falls below a predetermined value, means connecting said wattmeter to the first said means for operating the first said means to partially unload the compressor every time the wattmeter is energized, and a time delay mechanism energized and de-energized simultaneously with said wattmeter and connected so long as it is energized to operate the second said means after the lapse of a predetermined time from being energized for partially unloading the compressor.

2. The controller claimed in claim 1 in which said time delay mechanism while energized repeatedly operates the second said means to unload the compressor in a step by step fashion with a lapse of a predetermined time between each step.

3. The controller claimed in claim 1 in which said time delay mechanism is operatively connected to said wattmeter and energized and de-energized thereby.

4. The combination with a motor driven compressor having a plurality of unloading valves, each valve controlling part only of the compressor capacity, of a load controller comprising a valve operating mechanism connected to some of said valves and operable on starting up the compressor to operate all of the valves connected thereto to load the compressor to the expected starting maximum load, means operatively connected for operating other of said valves, a control element automatically responsive to variations in load on the driving motor and energized and de-energized alternately as the motor load exceeds and falls below a predetermined value, means operatively connecting said control element to the first said means to partially unload the compressor every time the control element is energized, and a time delay mechanism energized and de-energized simultaneously with said control element and operatively connected so long as it is energized to operate the first said means after the lapse of a predetermined time from being energized for partially unloading the compressor.

5. The controller claimed in claim 4 in which time delay elements are connected to said other of said valves operative on starting a loading cycle to close said other of said valves in delayed sequence to load the compressor in a step by step fashion.

6. The controller claimed in claim 5 in which the delay between steps in loading is greater than the predetermined time lapse between operating steps of said time delay mechanism.

7. The combination with a motor driven compressor connected to pump gas under pressure discharged at a pressure varying over a relatively large range and having a plurality of unloading valves, the overall variations being in one direction only, said compressor including a low pressure stage and a high pressure stage with each stage having valves with each valve controlling part only of the capacity of the stage in which it is connected, of a load controller comprising valve operating mechanism connected to the high pressure stage valves and some of the low pressure stage valves and operated on starting up the compressor to operate all valves connected thereto to load the high pressure stage to substantially full capacity and to partially load the low pressure stage, means operatively connected for operating the remaining low pressure valves, a control element automatically responsive to variations in load on the driving motor energized and de-

energized alternately as the motor load exceeds and falls below a predetermined value, means for operatively connecting said control element to actuate said means for partially unloading the compressor every time the control element is energized, and a time delay mechanism energized and de-energized simultaneously with said control element and connected so long as it is energized to operate the last said means after the lapse of a predetermined time from being energized for unloading the compressor in a step by step fashion.

8. The combination with a motor driven compressor having a plurality of unloading valves, each valve controlling part only of the compressor capacity, of a load controller comprising means operatively connected for operating each of said valves; a contact making watt meter connected to the motor power supply and energized and de-energized alternately whenever the motor load exceeds and falls below a predetermined value; a control electrical circuit comprising a plurality of parallel circuits each containing a normally open switch, a normally closed switch and a control relay, except the first actuated parallel circuit does not contain the normally closed switch and the last actuated parallel circuit does not contain a normally closed switch, and a master switch connected in series with said parallel circuits; a setup electrical circuit comprising a plurality of parallel circuits each containing a normally open switch and normally closed switch and an auxiliary relay, and a master switch connected in series with the last said parallel circuits and being operable in

30 a reverse fashion to the first said master switch; interconnecting normally open switches connecting the parallel circuits of the control and setup circuits; and a master relay connected to be actuated by said contact making watt meter and connected to actuate said master switches; said auxiliary and control relays, except for the first and last control relay to be actuated, being connected to operate a switch in the succeeding and preceding, in operating order, parallel circuit and an interconnecting switch, and said control relays being connected additionally to operate said means such that whenever the contact making watt meter is actuated into one position, one of the branch circuits of the control circuit is locked in energized to operate said means to partially unload the compressor and set up the succeeding branch circuit of the set up circuit to be locked in energized by a reverse of operation of the contact making watt meter to set up the succeeding parallel circuit of the control circuit.

9. The load controller claimed in claim 8 in which is provided a time delay circuit including time delay opening and time delay closing switches and actuating relays therefor interconnected with said contact making watt meter and control and setup circuits and arranged to be energized and de-energized with said meter and adapted in the event that the contact making watt meter is not de-energized within a predetermined length of time after being energized, to de-energize and energize the control and setup circuits in time delayed sequence in the same fashion as if the contact making watt meter were alternately de-energized and energized.

10. The combination with a motor driven compressor connected to pump gas under pressure and discharge such gas at a pressure varying over a relatively large range and having a plurality of unloading valves, the overall variations being in one direction only, said compressor including a low pressure stage and a high pressure stage with each stage having unloader valves with each valve controlling part only of the capacity of the stage in which it is connected of a load controller; comprising a plurality of valve operating mechanisms connected to severally operate said valves; a control element connected to the motor and operated in response to variations in load thereon to be actuated into alternate control positions by alternations of such load above and below a predetermined value; a control system having a master element and a plurality of actuating elements connected to control

the operation of said valve operating mechanisms; a setup system having a master element and a plurality of actuating elements controlled thereby; means connected to be operated by said control element and connected to each master element for actuating said master elements into different control positions each time the control element is actuated, said systems being interconnected such that each time the control element is actuated into one position, the master element of the control system is operated to power at least one of the associated actuated elements to actuate at least one of the valve operating mechanisms to partially unload the compressor, and each time the control element is actuated into another position the master element of the setup system is operated to power one of the actuating elements controlled thereby to set up a part of the control system such that it may be activated when the control element is again actuated into the first said position.

11. The load controller claimed in claim 10 in which a time delay unloading system is interconnected with the control and setup systems and said control element is energized and de-energized whenever the motor load exceeds or falls below said predetermined value, and said time delay unloading system is arranged in the event the control element is not alternated into said other position within a predetermined lapse time from being actuated

into the first said position to actuate said master control elements in time delay sequence and in the same manner as if the control element was actuated into alternate control positions.

- 5 12. The load controller claimed in claim 9 in which operatively connected means are provided to operate simultaneously several of said valve actuating mechanisms when the compressor is started up and additional operatively connected means are provided for operating the 10 remainder of said actuating mechanism in time delayed sequence to complete loading of the compressor in a step by step fashion.
